Attorney

UNITED STATES PATENT OFFICE.

GEORGE P. MILKENT, OF NILES, OHIO.

RAIL CHAIR.

Application filed March 24, 1923. Serial No. 627,440.

To all whom it may concern:

Be it known that I, GEORGE P. MILKENT, a citizen of the United States, residing at Niles, in the county of Trumbull and State 5 of Ohio, have invented new and useful Improvements in Rail Chairs, of which the following is a specification.

My invention relates to a rail splice or chair and has for its object the provision of 10 means which will hold the meeting ends of railroad rails in abutting relation at all times and also in alignment with each other.

It is well known that due to creeping as 15 well as wear and vibration, the meeting ends of rails very often become widely spaced thereby causing objectionable noise as the cars pass over these joints, and this defect also causes rapid destruction of the rails which require renewing from time to time.

20 It is also known that as the cars pass over the joints, slight vertical movement is imparted to both ends of the rail due to the wear of the rail splice and it has been found practically impossible to eliminate this slight

25 vertical movement. Applicant has recognized this fact and provides means which will still permit this slight vertical movement between the meeting ends of the rails, but which will not permit the ends to spread 30 unduly, leaving a large space between the two nor will it permit the warping of the tracks so that the ends are thrown out of longitudinal alignment.

With these and other objects in view, 35 which will appear more clearly as the specification proceeds, reference may be had to the accompanying drawings forming part of this specification, to illustrate the description and it is intended that minor changes 40 in the size, form or proportions of the various details may be made without departing from the spirit of the invention or the scope of the claims hereunto appended.

In the drawings:—

45 Fig. 1 is a plan view with a portion of the rail treads broken away to show the interior construction.

Fig. 2 is a vertical sectional view taken on the line X—X of Fig. 1.

50 Fig. 3 is a vertical sectional view taken on the line Y—Y of Fig. 1.

Referring more particularly to the drawings, 1 indicates a chair having cast or otherwise integrally formed therewith fish plates 55 2 and 3, the fish plate 2 being so formed as to closely engage one side of the rail 4, while

the fish plate 3 is spaced from the rail to provide a recess for the reception of a wedge plate 6. This wedge plate 6 is adapted to be inserted longitudinally of the chair and closely embraces the other side of the rail and is held securely in place by means of screw keys 7, screwed into openings 8 formed in the fish plate 3, the lower end of these screw keys adapted to contact with the wedge plate to prevent longitudinal movement thereof after the same have once been properly positioned. It is to be understood that various constructions of this screw key may be used. It may have a rounded base 70 adapted to engage recesses in the wedge plate or it may pass through screw threaded openings provided in the wedge plate to hold the same in place.

In the fish plate 2, I provide a chamber 9 which extends on both sides of the meeting ends of the rails 4 and 5 to receive therein locking members which engage the rail to prevent excessive longitudinal spreading of these rails. These locking members comprise 80 a plurality of blocks designated as 10, 11 and 12, the blocks 10 and 12 having integrally or otherwise formed thereon, projecting studs 13, and at each end of the meeting rails 4 and 5, I provide vertically elongated openings 14 to receive these studs. Interposed 85 between the studs, I mount the block 11, which is of such a width that it contacts with the side of the rail and with one side of the chamber, thereby preventing displacement 90 of the same. This block, 11, maintains the two blocks 10 and 12 in spaced relation so that the studs 13 are in proper alignment with the openings 14 and cannot become dislodged therefrom. It is seen therefore, that 95 these blocks 10 and 12 while preventing excessive longitudinal spread of the ends of the rails are loosely mounted in the chamber 9 and will, therefore, permit vertical movement of the meeting ends of the rail when 100 wear takes place, while the wedge 6 and the fish plate 2 prevent lateral movement of the rails, causing the meeting ends to be thrown out of alignment.

From the foregoing description, it can 105 readily be seen that as a car passes over this joint, the two rail ends 4 and 5 may be permitted to move vertically since it seems to be practically impossible to eliminate this movement, and yet will not be permitted to 110 creep so as to become widely separated.

The chair 1, may be secured to the ties in

suitable fashion and I have illustrated herein, ordinary rail spikes 15 which may be passed through suitable openings in the base or may be driven directly into the ties and 5 have the heads thereof in engaging relation with the chair.

The invention as described, clearly indicates that the same is easily assembled and can be disassembled very rapidly when it is 10 found necessary to remove one of the rails, by merely loosening the screw keys 7, removing the wedge plate 6, and by turning the rail 14 or chair so as to disengage the rail from the blocks and by sliding the chair and 15 rail relatively to each other, the locking blocks 10, 11 and 12 may then be removed. To assemble this rail chair, the reverse of the operation heretofore described is followed out, so that it is apparent that such 20 assembling and disassembling can be accomplished in a very few minutes.

It might further be noted that this chamber 9 is so positioned in the fish plate 2 that it lies wholly beneath the head of the 25 rail and is, therefore, protected to a considerable extent from the elements. This is desirable since if the chamber and locking blocks were exposed, rusting of the parts would make it difficult to disassemble the 30 rail chair, so that applicant has provided this means for protecting these members.

Applicant is aware of the fact that it is old to provide chairs having wedge plates to engage the rail and is also aware of the 35 fact that it is old to pass locking pins through the fish plate and into the web of the rail for the purpose of holding the same in place. However, applicant is not aware of the fact that it is old to provide locking 40 pins of the kind described herein which permit this vertical play of the rails but maintain them in proper position at all times,

and it is this feature of the invention to which applicant believes himself to be entitled.

I claim:

1. A rail chair comprising a base plate having integrally cast fish plates thereon engaging the rail, a wedge plate interposed between one of the fish plates and the rail, the said fish plate having openings therein to receive screw keys adapted to engage the wedge plate and hold the same against longitudinal movement, the other fish plate having a chamber therein extending on both sides of the meeting ends of the rails, the said rails having openings therein, blocks within the chamber having studs thereon engaging the openings in the rails and a spacing block interposed between the locking blocks to prevent dislodgment of the same. 55

2. A rail chair comprising a base having integrally cast fish plates thereon engaging the rail, a wedge plate interposed between one of the fish plates and the rail, the said fish plate having openings therein to receive screw keys adapted to engage the wedge plate and hold the same against longitudinal movement, the other fish plate having a chamber therein extending on both sides of 60

the meeting ends of the rails, the said rails having openings therein, locking blocks within the chamber provided with studs engaging the openings in the rail, a spacing block interposed between the locking blocks 75 to prevent dislodgment of the same, each of the locking blocks being slidably mounted in the chamber for vertical movement with the rails, the said chamber in the fish plate being located wholly beneath the rail head. 80

In testimony whereof I have hereunto set my hand.

GEORGE P. MILKENT.
